UNITED STATES PATENT OFFICE.

FRANK H. DURGIN, OF LE MARS, IOWA, ASSIGNOR OF ONE-HALF TO WILLIAM F. BELAU
AND ONE-HALF TO CHARLES J. MARCUE, OF LE MARS, IOWA.

DRAFT APPLIANCE.

No. 918,426.

Specification of Letters Patent.

Patented April 13, 1909.

Application filed December 9, 1908. Serial No. 466,668.

To all whom it may concern:

Be it known that I, FRANK H. DURGIN, a citizen of the United States, residing at Le Mars, Iowa, in the county of Plymouth 5 and State of Iowa, have invented a new and useful Draft Appliance, of which the following is a specification.

The object of the present invention is to provide a bracket which may be applied to 10 an ordinary wagon, such as a lumber wagon, without altering the structure of the running gear of the wagon in any way whatsoever, and will serve as a means for the attachment and support of an equalizer bar so constructed 15 as to have a greater number of draft animals travel to one side of the tongue than to the other side, and one of the primary objects of the invention is to so construct the bracket as to equally and evenly 20 distribute the strain upon the running gear.

In the accompanying drawings:—Figure 1 is a top plan view of the forward portion of the running gear of an ordinary vehicle, such as that of a lumber wagon, showing the 25 application of the invention thereto; Fig. 2 is a perspective view of the bracket, removed from the vehicle running gear.

In the drawings the hounds of the running gear are indicated by the numeral 5, the reach by the numeral 6, and the sand-board by the numeral 7; the tongue of the vehicle being indicated by 8.

The attachment embodied in the invention consists of a bracket member and a 35 brace for holding said member in proper position upon the vehicle running gear, and the bracket member is in the nature of a bar 9, which, at its rear end, is bent downwardly at right angles as at 10, and thence 40 beneath its body portion as at 11, so as to receive or embrace a portion of the reach 6 of the vehicle running gear. Inwardly of the reach-engaging end of the bar, it is offset in an upward direction, as indicated by 45 the numeral 12, so as to bring the body portion of the bar in a plane above the sand-board 7. The bar 9 has its rear portion extended substantially in the arc of a circle laterally, and has its forward portion ex- 50 tended directly forwardly in a line substantially parallel with the line of extent of the reach 6. Secured upon the bar at its forward end is a hammer strap 13, through the extremity of which and the said extremity 55 of the bar, is passed a bolt 14. The bolt 14

just mentioned is passed also through an equalizer bar or beam 15, which is received between the hammer strap and the forward extremity of the bar 9, and to this equalizer bar is connected a swingle-tree 16, and a 60 double-tree 17, to which latter are connected swingle-trees 18, two swingle-trees being, in this manner, arranged and supported to one side of the vehicle tongue 8, and a single one of the trees to the other side of the said 65 tongue.

In addition to being passed through the extremities of the hammer strap, bar 9, and the equalizer beam 15, the bolt 14 passes also through the forward end of a brace bar 19, to 70 the rear end of which is pivoted an attaching bolt 20. This bolt has threaded upon it a nut 21, and, in applying the device to a vehicle, the bolt is passed from front to rear through the sand-board 7, and the nut 21 is 75 then threaded upon the bolt and tightened. The point of attachment of the forward end of the brace bar 19 to the bracket 9 is to one side of the line of extent of the reach 6, and the point of attachment of the rear end of the 80 said brace bar to the sand-board 7 is to the other side of the said line of extent of the reach, the brace bar being extended rearwardly diagonally in advance of the sand-board, as clearly shown in Fig. 1 of the draw- 85 ings.

From the foregoing description of the invention it will be observed that the device embodied therein may be readily and quickly applied to the running gear of any 90 ordinary vehicle of that type which requires several draft animals, and that, by reason of the peculiar location and arrangement of the brace bar 19 and its manner of connection with the running gear of the vehicle and with 95 the bracket member of the device, the strain or stress upon the running gear is equalized, or in other words, equally distributed to opposite sides of the line of extent of the reach, lateral stress being effectually overcome. 100

What is claimed is:—

1. In a draft equalizer, the combination with a vehicle reach and sand-board, of a bracket secured at one end to the reach and extended laterally and thence forwardly to a 105 point forwardly of the sand-board and to one side of the line of extent of the reach, the said bracket being arranged at its forward end to support an equalizer bar, and a brace se- 110 cured to the forward end of the bracket and

to the said sand-board at a point to the other side of the line of extent of the reach.

2. In a draft equalizer, the combination with a vehicle reach and sand-board, of a 5 bracket secured at its rear end to the reach, said bracket being arranged at its forward end to support an equalizer bar lying to one side of the line of extent of the reach, and a brace bar secured at its forward end to the 10 forward end of the bracket and extending diagonally in front of the sand-board and secured at its rear end to the said sand-board at a point to the other side of the line of extent of the reach.
- 15 3. An attachment of the class described comprising an arcuate bar having one end formed to embrace a vehicle reach, the said

bar being provided at its other end with a hammer strap for the attachment of an equalizer bar, a bolt passed through the hammer 20 strap and the end of the arcuate bar, a brace bar, through one end of which said bolt is also passed, whereby to pivot the said brace bar at its said end to the arcuate bar, and an attaching bolt pivoted to the other end of the 25 said brace bar.

In testimony that I claim the foregoing as my own, I have hereto affixed my signature in the presence of two witnesses.

FRANK H. DURGIN.
